CLAIM

The ornamental design for a prosthetic article as shown and described.

DESCRIPTION

FIG. 1 is a perspective view showing the new design for the prosthetic article;

FIG. 2 is a rear view showing the new design for the prosthetic article;

FIG. 3 is a front view showing the new design for the prosthetic article;

FIG. 4 is a right side view showing the new design for the prosthetic article;

FIG. 5 is a left side view showing the new design for the prosthetic article;

FIG. 6 is a top view showing the new design for the prosthetic article; and,

FIG. 7 is a bottom view showing the new design for the prosthetic article.

The broken lines in the drawings depict portions that form no part of the claimed design.
